UNITED STATES PATENT OFFICE.

THEODORE A. JOHNSON, OF PORTLAND, MAINE.

IMPROVEMENT IN FOOT-RESTS FOR CHAIRS.

Specification forming part of Letters Patent No. 136,734, dated March 11, 1873.

To all whom it may concern:

Be it known that I, THEODORE ALFRED JOHNSON, of Portland, in the county of Cumberland and State of Maine, have invented certain new and useful Improved Extensible Foot-Rest for Chairs; and I do hereby declare that the following is a full, clear, and exact description thereof, that will enable others skilled in the art to which it appertains to make and use the same, reference being had to the accompanying drawing and to the letters of reference marked thereon which form a part of this specification.

The purpose of this invention is to provide a foot-rest for chairs of a new and improved construction, which may be attached to any chair without the prerequisite of any peculiar formation of the chair.

The construction of the foot-rest may be learned from the following description: Secured by pivots or screws to the front or bottom of the chair, either to that portion placed for ornamental purposes beneath the front rail of the chair, or, when a wider rest is desired, to the inner side of the legs, are two arms, the other ends of which are pivoted to the foot-rest at each side. The points at which the arms are pivoted to the rest are determined by considerations hereafter adverted to.

The rest may be either single or capable of extension. To render it extensible two parallel grooves of the shape of an inverted T (or of such other form as may be as well adapted for the purpose) are made near to and parallel to the sides of the rest to which the arms are attached, extending a greater or less portion of its length, as desired. In each of these grooves are placed T-shaped teeth, two or more in number, which are so attached to another rest as to admit of the teeth sliding freely in the grooves when it is wished to extend or make shorter the rest. At the back of the rest are placed one or more hooks, while upon the front of the rail of the chair are inserted the like number of hooks or catches in corresponding positions into which the hooks upon

the rest may be inserted. Beneath the chair at the back is fixed a hook. (See *a* in the drawing.) The arms must be of such length that when in use the back of the rest will be in contact or almost in contact with the front of the chair, so as to allow the hooks to be placed in the catches; and when not in use, and the rest is placed beneath the chair, no part of the rest will project beyond the front of the chair.

In the drawing, *c* shows the arms; *b*, the rest containing the grooves *f*; *d* is the extensible portion of the rest, and *e* the hooks attached to the rest. *a* is the hook placed beneath the back of the chair.

The operation of the foot-rest will be readily seen. When in use it is placed in the position shown in the drawing, it being sustained by the hooks which are inserted upward into the catches. When it is desired to put the rest beneath the chair the hooks are removed from the catches and the rest, still preserving a horizontal position, is swung under the chair, the ends of the arms describing the semicircle shown in dotted lines in the drawing, the back of the rest being placed upon the hook *a*, where it is supported, its position under the chair being shown in dotted lines. If the weight of the rest is so great as to prevent its being thus supported, the result may be effected by placing a button or like contrivance under the front rail of the chair.

What I claim as my invention is—

The detachable foot-rest herein described, consisting of the arms *c*, piece *b*, (with or without the piece *d*), hooks *e*, and catches and the hook *a* or its equivalents, constructed and applied substantially as herein set forth.

In testimony that I claim the foregoing I have hereunto set my hand this 22d day of January, 1873.

THEODORE A. JOHNSON.
